DISPLAY DEVICE

Sydney Charles Gill and Sydney Dallaway,
London, EnglandApplication August 11, 1934, Serial No. 739,499
In Great Britain April 6, 1933

10 Claims. (Cl. 272—13)

This invention relates to display devices, more particularly to display devices employing the well known "Pepper's ghost" illusion.

According to the present invention an opaque member forming about a quarter of a sphere is mounted for rotation substantially about its geometrical centre, which at the same time forms its sole point of support. The member may be formed of a hollow semi-sphere, which, when 5 made of metal, has substantially one half thereof removed, whilst, when made of transparent material, has substantially one half thereof rendered opaque. In the hollow member is preferably mounted a lamp for illuminating purposes, 10 the heat of this lamp serving to rotate the member. When using the member with a transparent screen inclined to the horizontal, the geometrical centre of the member is preferably located directly above the upper edge of the screen so that on 15 rotation of the member above the screen there is a gradual change from dark to light or vice versa on opposite sides of the screen so that objects located on opposite sides of the screen appear, when viewed in the screen, as merging 20 one into the other.

The invention will now be described with reference to the accompanying drawings, wherein:—

Fig. 1 shows a front elevation of a display device, the front door being omitted.

Fig. 2 shows a section on the line 2—2 of Fig. 1.
Fig. 3 shows a sectional plan, and

Fig. 4 shows a sectional elevation of a portion of a slightly modified form of the device.

As shown in Figs. 1 to 3, a transparent screen 1, preferably composed of tinted glass layers, such as anti-dazzle glass sold on the market under the registered trade-mark "Triplex", is mounted so as to be inclined forwardly at an angle of about 45° in a casing 2.

Centrally above the upper edge of the screen 1 is arranged a rotary hollow member formed of a circular base plate 4 from which depends a semi-spherical bowl 3. One half of this bowl 3 is transparent whilst the other half is opaque. The 45 same result may be obtained by omitting one half 5 of the bowl 3 as shown. At the centre of the base plate is provided a cup-shaped bearing 6 which engages with a pivot 7 attached to a support 8 carried on the upper edge of the screen 1 50 or by a cross piece secured to the casing and extending just above the upper edge of the inclined screen and parallel thereto. The support may, however, be secured in position in any other suitable manner. The pivot 7 and bearing 6 form 55 the sole support for the bowl 3 and are so ar-

ranged that the bowl is supported and rotates substantially about its geometrical centre. Such an arrangement has the advantage that it avoids fine adjustment of the casing for ensuring that the bowl takes up its absolutely central position above the upper edge of the screen.

The base plate 4 of the bowl is preferably made of light metal, such as aluminium, and is provided with blades or vanes 10, which are cut therefrom, for the purpose of its rotation as hereinafter described.

The bowl may be made of glass or other transparent material, one half thereof being made opaque. The bowl may, however, consist only of half a semi-sphere, which is opaque, and is preferably made of light metal, such as aluminium. In order to avoid undesired reflection, the opaque portion is preferably provided inside at 3a and outside at 3b with a matt black coating.

The bearing support 8 extends into the bottom 20 of the bowl 3 through an opening 11 in the latter and preferably consists of one or more loops, to which there are secured the pivot 7 and a socket 12 for an incandescent electric lamp 13. The leads 14 for this lamp extend to the support 8 25 and its carrier 15, or, when the latter is hollow, as shown, they are located in the interior thereof.

The heat of the lamp 13 serves to create air currents, which in passing over the blades or vanes 10 serve to rotate the bowl 3. Balancing 30 means, such as an extra thickness of metal or a drop of lead, serve to balance the coating or the bowl member when this is formed as half of a semi-sphere.

Above the upper edge of the screen 1, there is 35 mounted a vertical plate 16, preferably blackened on both sides as indicated at 16a and 16b, of which the lower edge extends parallel with the upper edge of the screen 1 and abuts against this. The plate 16 may be of any suitable material such as cardboard, metal or wood. This plate 16 extends upwardly to about the level of the base plate 4 and is provided with a semi-circular cut-out portion 17 to receive the bowl 3. 40 A slight clearance is left between the cut-out portion 17 and the bowl 3 to permit of free movement of the latter. A small circular or semi-circular disc 18 is also secured horizontally in the cut-out portion 17 adjacent the opening 11 in the bowl 3 so as to prevent light from the lamp 13 45 from passing through the opening 11 in the bowl 3.

In the back 19 of the casing, one or more objects 19a are arranged behind the screen 1 which are adapted to be viewed through the screen and through an aperture 20 in the front of the cas- 50 55

ing 2. In the bottom 21 of the casing, in front of the screen 1, are also placed one or more objects 21a adapted to be viewed through the aperture by reflection in the screen.

5 In the front panel of the cabinet may be provided a second aperture 22, above the first 20, in which may be placed an inscription dealing with the objects in front of and behind the screen. This aperture is preferably arranged on the same 10 level as the bowl 3.

Above the base plate 4 there may also be mounted an apertured plate 23 or a crossbar 23a, which at the centre is provided with a hollow boss or ring 24 extending in spaced relation around 15 the bearing 6 so as to prevent this from being disengaged from the pivot 7. The boss 24 and pivot 7 or bearing 6 may be made adjustable if desired.

In use the lamp 13 when illuminated sets up by reason of its heat a current of air which passes 20 over the blades or vanes 10 and thus rotates the bowl 3. The air after passing the blades 10 passes upwardly through the apertures in the plate 23 above the base plate 4 or around the cross bar 23a and then out of the cabinet, which 25 may be provided with a suitable cowl or chimney.

On the rotation of the bowl 3 the screen 1 is illuminated by the light passing through the transparent or open half 5 of the bowl 3, the illumination on opposite sides of the screen 1 being 30 gradually cut off or increased so that when looking into the aperture 20 the articles in front of and behind the screen 1 appear gradually to merge one into the other, whilst the inscription in the aperture 22 gradually appears and disappears.

For the purpose of levelling the cabinet, it is preferably mounted on three adjustable feet 25.

The second aperture 22 may contain a sheet 22a of plain or frosted glass 3.

40 In the modification shown in Fig. 4 a rod 26 is detachably secured, as by screws 27, to the plate 16. The rod 26 carries the boss 24 and at its ends is provided with hooks or loops 28. Between these hooks or loops 28 extends an elastic band 29 which 45 when in the chain-dotted position raises the bowl 3 whereby the bearing 6 is raised off the pivot 7 and moves a cone 30 into a conical seat 31 in the boss 24. This arrangement is particularly suitable for preventing the bowl 3 from rocking during transport.

50 In this construction two lamps 32 and 33 are provided.

In order to project the light downwardly from the lamp 13 or the lamps 32 and 33, a reflector 34 55 is carried by the support 8, whilst a further reflector 35 is carried by the front part of the casing 1.

We claim:

1. In a display apparatus the combination with 60 a transparent screen inclined substantially at 45° to the horizontal, of an opaque member forming about a quarter of a sphere, mounting means for said member, said member being mounted in said mounting means above said screen substantially 65 about its geometrical centre; said geometrical centre being located vertically above the upper end of the screen and forming the sole point of support for said member, said member comprising a base of metal, a plurality of vanes in said base, 70 and a body forming substantially a quarter of a sphere depending from said base, and a source of light located in said body, the arrangement being such that the heat from the source of light in passing between said vanes, said member is caused 75 to rotate whereby the light from the source of

light alternately illuminates opposite sides of the screen, the change in illumination of the opposite sides of the screen being effected gradually as a result of the rotation of the member.

2. In a display apparatus the combination with 5 a casing, and a screen located at an angle of about 45° to the horizontal in said casing, of a supporting frame mounted in said casing, above said screen, a bearing element carried by said supporting frame, a semi-spherical member, a bearing element carried by said semi-spherical member, said bearing elements cooperating with one another and forming a centre of rotation for said member, said centre of rotation being substantially at the geometrical centre of said member 10 and being located directly above the upper edge of said screen, said member having substantially one half thereof opaque and the remainder thereof of transparent, a plurality of vanes located at the diametrical plane of said member, and a 20 source of light located in said member.

3. A display apparatus of the character described comprising a casing, an inclined screen in said casing, a support carried by the upper end of said screen, a bearing element carried by said support, a hollow member, said member comprising a circular base and a semi-spherical bowl secured to said base, said bowl having one half thereof transparent and the remainder opaque, a bearing element on said base plate, said bearing element cooperating with the first mentioned bearing element and forming therewith a centre of rotation for the hollow member, said centre of rotation being located at the geometrical axis 30 of the hollow member, a source of light mounted 35 on said support and inside said hollow member, a plurality of vanes on the said base, said casing having a viewing aperture in the front thereof opposite said screen, a back on said casing, said back being adapted to receive an article to be 40 viewed through said aperture and said screen, and a bottom in said casing, said bottom being adapted to receive an article to be viewed through said aperture by reflection in said screen.

4. A display apparatus of the character described comprising a casing, an inclined screen in said casing, a support carried by the upper end of said screen, a bearing element carried by said support, a hollow member, said member comprising a circular base and a semi-spherical bowl 45 secured to said base, said bowl having one half thereof transparent and the remainder opaque, a bearing element on said base plate, said bearing element cooperating with the first mentioned bearing element and forming therewith a centre 50 of rotation for the hollow member, said centre of rotation being located at the geometrical axis of the hollow member, a source of light mounted on said support and inside said hollow member, a plurality of vanes on the said base, said casing 55 having a viewing aperture in the front thereof opposite said screen, a back on said casing, said back being adapted to receive an article to be viewed through said aperture and said screen, and a bottom in said casing, said bottom being adapted to receive an article to be viewed through 60 said aperture by reflection in said screen, said casing having a second aperture therein, said second aperture being located above the first mentioned aperture and on the same level as the hollow 65 member.

5. A display apparatus of the character described comprising a casing, an inclined screen in said casing, a support carried by the upper end of said screen, a bearing element carried by 70 75

said support, a hollow member, said member comprising a circular base and a semi-spherical bowl secured to said base, said bowl having one half thereof transparent and the remainder opaque, 5 a bearing element on said base plate, said bearing element cooperating with the first mentioned bearing element and forming therewith a centre of rotation for the hollow member, said centre of rotation being located at the geometrical axis 10 of the hollow member, a source of light mounted on said support and inside said hollow member, a plurality of vanes on the said base, said casing having a viewing aperture in the front thereof opposite said screen, a back on said casing, said back being adapted to receive an article to be viewed through said aperture and said screen, and a bottom in said casing, said bottom being 15 adapted to receive an article to be viewed through said aperture by reflection in said screen, a partition extending across the casing above said screen, said partition having a cut out portion adapted to accommodate the hollow member with a slight clearance, a disc in said cut out portion directly below the hollow member, a reflector inside said hollow member and above said source of light, and a second reflector inside said casing at the front thereof, said second reflector being adapted to reflect the light from said light source 20 down the front of said screen.

30 6. A display apparatus of the character described comprising a casing, an inclined screen in said casing, a support carried by the upper end of said screen, a vertical pivot on said support, a hollow member, said member comprising a circular base and a semi-spherical bowl secured to said base, said bowl having one half thereof transparent and the remainder opaque, an inverted cup-shaped bearing on said base plate, said bearing and pivot forming the sole support for 35 said hollow member and being so arranged that the hollow member is supported and is capable of rotation about its geometrical centre, a source of light mounted on said support and inside said hollow member, a plurality of vanes on said base, said casing having a viewing aperture in the front thereof opposite said screen, a back on said casing, said back being adapted to receive an article to be viewed through said aperture and said screen, and a bottom in said casing, said bottom being 40 adapted to receive an article to be viewed through said aperture by reflection in said screen.

45 7. A display apparatus of the character de-

scribed comprising a casing, an inclined screen in said casing, a support carried by the upper end of said screen, a bearing element carried by said support, a hollow member, said member comprising a circular base and a semi-spherical bowl secured to said base, said bowl having one half thereof transparent and the remainder opaque, a bearing element on said base plate, said bearing element cooperating with the first mentioned bearing element and forming therewith a centre 5 of rotation for the hollow member, said centre of rotation being located at the geometrical axis of the hollow member, a source of light mounted on said support and inside said hollow member, a plurality of vanes on the said base, said casing having a viewing aperture in the front thereof opposite said screen, a back on said casing, said back being adapted to receive an article to be viewed through said aperture and said screen, and a bottom in said casing, said bottom being 10 adapted to receive an article to be viewed through said aperture by reflection in said screen, a spider at the top of the casing, a recessed boss at the centre of said spider, said boss being normally spaced from the second mentioned bearing, attaching means in said casing, and a flexible band extending between said attaching means, said flexible band when attached to said attaching means being adapted to raise the hollow member 15 so as to move the second bearing element away from the first bearing element and into engagement with said boss.

20 8. A display apparatus according to claim 2, wherein the member comprises a hollow semi-sphere of metal of which substantially one half 25 thereof is removed.

30 9. A display device according to claim 2, wherein the member is made of transparent material in the form of a hollow semi-sphere, substantially one half thereof being rendered opaque.

35 10. A display apparatus according to claim 2, wherein the member comprises a sheet metal hollow semi-spherical member, said member having substantially one half thereof cut away so as to leave approximately a quarter of a hollow sphere, 40 a disc extending across the base of said member, said disc being slotted so as to form partly detached portions, said portions being slightly bent to form vanes.
